UNITED STATES PATENT OFFICE.

EDWARD B. HESS, OF BROOKLYN, NEW YORK, ASSIGNOR TO ROYAL TYPEWRITER COMPANY, OF NEW YORK, N. Y., A CORPORATION OF NEW JERSEY.

TYPE-WRITING MACHINE.

1,074,098.

Specification of Letters Patent. Patented Sept. 23, 1913.

Original application filed November 24, 1905, Serial No. 288,968. Divided and this application filed September 19, 1912 Serial No. 721,230.

To all whom it may concern:

Be it known that I, EDWARD B. Hess, a citizen of the United States of America, residing in the borough of Brooklyn, county 5 of Kings, and State of New York, have invented a certain new and useful Improvement in Type-Writing Machines, of which the following is a specification.

This invention relates to devices particularly applicable to cards and provides for so holding the card that it may be printed upon closely adjacent its top and bottom and also its side edges.

The construction is hereinafter described 15 in detail.

This application is a division of my application filed November 24, 1905, Ser. No. 288,968.

In the accompanying drawings: Figure 1 20 is a front elevation; Fig. 2, a partial or detail front elevation showing in lowered or inactive position an adjustable card or paper holder; Fig. 3, a perspective view of such paper holder detached; Fig. 4, a side 25 view thereof; Fig. 5, a general plan; and Fig. 6, a section on the line 6, 6, of Fig. 5.

The cylindrical platen 1 is mounted to rotate in bearings in the side plates 2, 2, of the transversely reciprocating carriage frame. 30 Somewhat in rear of the platen, there extends between the side plates a transverse shaft 3 shown as square or angular in cross section.

4 is the type bar segment; 5, an ordinary 35 type bar guide; and 6, an ordinary ribbon vibrator.

7 indicates a scale coöperating with the platen, located below and closely adjacent the printing line and traveling with the 40 platen.

The scale may be spring pressed (springs not shown) against the platen as disclosed in my original application of which this case is a division.

45 On the transverse bar 3 are mounted so as to be capable of longitudinal movement thereon bracket arms 8 that extend forward over the platen and have attached thereto paper guide plates or fingers 9, the ends of 50 which extend down or around the front of the platen and overlap the scale 7. At a point above the line of print, the arms 9

have lugs 10 turned up at their edges; and in these lugs are mounted pressure rolls 11 that bear upon the platen through openings 55 formed in the arms or plates 9. The plates 9 and rolls 11 are particularly margin paper guides and clamps. Intermediate the margin clamps is a paper holder 12 that extends forward over the platen and is rounded or 60 curled up at its forward end 12' which terminates above the line of print. This intermediate or central card and envelop clamp 12 is carried by the transverse shaft 3 but is divided transversely, its front paper holding part 12 being hinged somewhat in front of its roller box which is mounted on the shaft 3 and is capable of longitudinal movement thereon. Such hinge connection is marked 13. It may be formed by cutting a 65 slot 14 in the plate 15 that projects forward from the roller box that embraces the shaft 3 and has rollers 16 that run against the under side of the shaft. The two bifurcations formed by the slot 14 are turned up at their 70 ends to provide bearings for a hinge pin 17 that also passes through lugs 18 turned up at the rear side edges of part 12. An upward projection 19 at the rear edge of the part 12 lies in the slot 19. When the paper 75 holder 12 is raised, this projection passes down in the slot 14 and depresses a leaf spring 20, the reaction of which upon the projection holds the part 12 in elevated position; and, when said part is thrown down 80 into working position, the spring bears against its under face beneath its pivot and holds the front end 12' down. The paper holder 12 may, therefore, be folded backward to a substantially horizontal position quite 85 out of the way of sheets discharged from the platen. This center paper holder is, as a whole, adjustable longitudinally with reference to the printing line and, as shown, it is set immediately in line with the printing 90 point above which its curled or rounded end terminates.

In the construction thus far described, there is mounted upon and traveling with the carriage frame, a platen, margin clamps 100 and guides, a center paper holder and the scale. In conjunction with these devices, I provide a paper holding device adapted to be applied at will to the paper adjacent the

printing point for the purpose of holding the paper against the surface of the platen. This device is particularly useful in connection with cards and with manifold work as an assemblage of sheets is liable to bulge or stand away from the platen. This card holding device is, in the particular form illustrated, composed of a lever arm 22 pivoted at 23 on the type bar segment. There is a plate spring 24 attached to the upper face of the segment and working against the square or angular lower end of the lever arm acts to hold it in elevated or depressed position. A link 25 connects the arm 22 above its pivot with a bell crank lever 26 pivoted in a bracket or projection on the frame of the machine, and a spiral spring 27 applied to the link tends to hold the arm 22 in upright position. In the end of the arm or lever 22 is a roller 28 whose axis is inclined to the longitudinal axis of the lever arm and is transverse to that of the platen. When the roller is in operative position, adjacent one side of the ribbon vibrator, its carrying arm or lever 22 is inclined away from it toward the side of the machine. The lever arm swings in a plane parallel with the axis of the platen and when elevated the roller comes into such juxtaposition to the surface of the platen as to prevent material springing of the cards or paper away from the platen. The angle of the arm and its flat edge against which the spring 24 bears when the arm is depressed are such that the arm 22 and roller lie well below the scale and behind the usual ribbon that passes through the vibrator, and is out of the path of sheets fed to the machine. At each side of the roller 28 the arm is formed with deflectors 29, inclined or curved away from the platen and acting to deflect, between the roller and the platen, cards, paper or envelop flaps that might tend to pass outside of the roller or to collide with it. The card holding surface 28 (which, in the form illustrated, is a roller) is closely adjacent the edge of the ribbon vibrator and is therefore quite near the printing point. This surface or roller 28 so coöperating with the platen extends from below across or above the line of print. It serves to hold cards, envelops or sheets closely against the platen and in the transverse movements of the platen prevents the edges of such cards, sheets and envelops coming in contact with the ribbon or ribbon vibrator.

It will be observed that the paper holding and guiding rollers 11 coöperate with the platen in a line above or beyond that in which lies the end of card holder 28 and also that the center card holder 12 terminates above the line of print and in a line above the end of the card holder and guide 28, 29. The drawing shows but one such card holder 65 and guide 28, 29 and hence it has been

shown on the right hand side of the ribbon vibrator because, if there be but one, it is most effective at that point.

The paper holding means lying across the line of print adjacent the printing point terminates a short distance above the upper edge of the vibrator and hence does not constitute a material obstruction to the operator's view of the front surface of the platen which in a machine such as that disclosed is quite open so that matter printed upon a sheet in the machine may be read with considerable facility.

I claim:

1. In a visible writing machine, the combination with the platen of a paper holder comprising an arm pivoted in front of the platen and capable of being rocked transversely of the machine from normal substantially horizontal position to an upright position into operative relation to the platen and having at its operative end forwardly inclined paper deflectors. 80

2. In a visible writing machine, the combination with the platen of a paper holder comprising an arm pivoted in front of the platen and capable of being rocked transversely of the machine from normal substantially horizontal position to an upright position into operative relation to the platen. 90

3. In a visible writing machine the combination with the transversely movable platen of a paper holder stationary with respect to the transverse movement of the platen, mounted in front thereof, extending across the line of print adjacent the printing point and movable transversely of the machine to below the line of print and out of operative relation to the surface of the platen. 100

4. In a visible typewriting machine, the combination with the platen of a paper holding device adapted to hold the paper against the platen adjacent the printing point and comprising a roller that lies across the line of print and whose axis is transverse to that of the platen. 110

5. In a visible typewriting machine the combination with the platen of a paper holding device mounted on the frame of the machine and adapted to hold the paper against the platen adjacent the printing point and comprising a roller that lies across the line of print and whose axis is transverse to that of the platen. 115

6. In a visible typewriting machine, the combination with the transversely movable platen of a paper holding device stationary with respect to the transverse travel of the platen and adapted to hold the paper against the platen adjacent the printing point and comprising a roller that lies across the line of print and whose axis is transverse to that of the platen and paper holding devices extending over the platen from the rear there- 125 130

of and coöperating with the first named device to hold the paper being printed upon.

7. In a visible typewriting machine the combination with the transversely movable 5 platen of a paper holding device stationary with respect to the transverse travel of the platen and adapted to hold the paper against the platen adjacent the printing point and comprising a roller that lies across the line of print and whose axis is transverse to that of the platen and paper holding 10 devices extending over the platen from the rear thereof and coöperating with the first named device to hold the paper being printed upon and means whereby the paper holding 15 devices extending over the platen may be swung rearwardly into inoperative position.

8. In a visible typewriting machine, a 20 transversely movable platen carriage, paper holding and guiding devices comprising a paper holder having a paper holding roller that lies across the line of print and whose axis is transverse to that of the platen located adjacent the printing point and stationary with respect to the traverse of the carriage, and coöperating roller clamps traveling with the platen.

9. In a visible typewriting machine, a 30 transversely movable platen carriage, paper holding and guiding devices comprising a paper holder having a roller that lies across the line of print and whose axis is transverse to that of the platen located adjacent the printing point and stationary with respect to the traverse of the carriage, coöperating roller clamps traveling with the platen and a scale bar traveling with the platen and overlapped by the clamps.

40 10. A visible writing machine have a transversely movable cylindrical platen, its carriage, a ribbon vibrator located in front of the platen and normally below the printing point thereon, a device stationary with respect to the transverse movement of the 45 platen for holding the paper against the platen and protecting it from contact with the ribbon in the vibrator, said device being arranged adjacent the printing point, and 50 extending above and below the printing line and provided with means to direct the side edge of the paper.

11. A visible writing machine having a 55 transversely movable cylindrical platen, its carriage, a ribbon vibrator located in front of the platen and normally below the printing point thereon, a device stationary with respect to the transverse movement of the platen for holding the paper against the platen and protecting it from contact with the ribbon in the vibrator, said device being arranged adjacent the vibrator and extending above and below the printing line and provided with means to direct the side edge 60 of the paper, combined with spring pressed

rolls mounted upon the platen frame and adapted to bear against the platen above said paper holding device.

12. A visible writing machine comprising a transversely movable platen, pressure 70 rolls mounted upon the platen frame and adjustable thereon laterally to contact with the material to be printed upon above the printing line, a scale located below the printing line, a vibrator carrying a ribbon also normally located below the printing line, an 75 arm stationary with respect to the transverse movement of the platen adjacent the vibrator supported below the point of contact of said pressure rolls with the platen and extending across the printing line and acting to hold the material being printed upon against the platen and a deflecting portion carried by the arm.

13. In a visible writing machine, the combination of a revoluble transversely movable platen, a paper holder permanently mounted on the machine, stationary with respect to the transverse movement of the platen and having a paper holding surface 90 that coöperates with the surface of the platen and extends across the line of print adjacent the printing point and is mounted to be moved downwardly from in front of and out of operative relation to the surface 95 of the platen and to remain in such inoperative position.

14. In a visible writing machine, the combination of a revoluble transversely movable platen, a paper holder stationary with 100 respect to the transverse movement of the platen and having a paper holding surface that coöperates with the surface of the platen and extends across the printing line adjacent the printing point and is pivoted to be swung downwardly from in front of and out of operative relation to the surface 105 of the platen and to remain in such inoperative position.

15. A visible writing machine comprising 110 the combination of a transversely movable rotatable platen, a paper holder arranged in front of the platen and extending upwardly across the line of print to hold the paper at the printing point close against the platen, a 115 coöperating paper holding device extending downwardly and terminating above the line in which the upper end of the first named holder lies and means whereby the first named holder may be moved downwardly 120 from in front of and out of operative relation to the printing surface of the platen and to remain in such inoperative position.

16. In a front strike writing machine, the combination with the transversely movable 125 rotatable platen of a paper holder stationary with respect to the transverse movement of the platen, supported below and in front of the platen, adapted to lie away from the printing surface of the platen so as not to 130

- obscure the operator's view of the printing line and movable to a position across the printing line alongside the printing point and then acting to hold paper at the side of the printing point against the platen.
17. In a front strike writing machine, the combination with a platen of a paper holder supported below and in front of the platen and normally located below the printing line and movable to a position across the printing line alongside the printing point and having a convexly curved surface co-operating with the surface of the platen to direct the paper in its transverse movement between it and the platen and acting to hold paper at the side of the printing point against the platen.
18. In a front strike writing machine, the combination with a platen of a paper holder supported in front of the platen below the printing line and movable to a point above the printing line and having forwardly flared side edges acting to direct the paper between it and the platen.
19. In a visible writing machine, the combination of a revolute transversely movable platen, a paper holder stationary with respect to the transverse movement of the platen and having a paper holding surface that co-operates with the surface of the platen and extends across the printing line adjacent the printing point and is adapted to be moved into and out of operative relation to the surface of the platen and manually controlled means comprising a link and a lever operatively connected with said paper holder whereby the latter may be moved into and out of operative relation to the platen.
20. In a visible writing machine, the combination of a revolute transversely movable platen, a paper holder stationary with respect to the transverse movement of the platen and having a paper holding surface that co-operates with the surface of the platen and extends across the printing line adjacent the printing point and is adapted to be moved into and out of operative relation to the surface of the platen and manually controlled means comprising a lever acting to effect movement of said paper holder into operative relation to the platen.
21. In a visible writing machine, the combination with a transversely movable rotatable platen of a paper holder stationary with respect to the transverse movement of the platen, normally located below the printing line on the platen and movable to operative position across said printing line adjacent the printing point to hold paper at the side of the printing point against the platen.
22. In a front strike typewriting machine, the combination of a transversely movable rotatable cylindrical platen, means seg-

mentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line thereon and adapted at each printing operation to be moved, substantially vertically, upwardly to carry the ribbon across the printing point thereon, and paper holding means forming a permanent structural element of the machine fixed with respect to the transverse movement of the platen and extending upwardly in front of the platen across the printing line adjacent the printing point to hold the paper away from the ribbon and toward the platen.

23. In a front strike typewriting machine, the combination of a transversely movable rotatable cylindrical platen, means segmentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line thereon and adapted at each printing operation to be moved, substantially vertically, upwardly to carry the ribbon across the printing point thereon, paper holding means forming a permanent structural element of the machine fixed with respect to the transverse movement of the platen and extending upwardly in front of the platen across the printing line adjacent the printing point to hold the paper away from the ribbon and toward the platen, and paper guiding means traveling and co-operating with the platen and terminating above said paper holding means.

24. In a front strike typewriting machine, the combination of a transversely movable rotatable cylindrical platen, means segmentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line thereon and adapted at each printing operation to be moved, substantially vertically, upwardly to carry the ribbon across the printing point thereon, a scale located below the line of print, and paper holding means forming a permanent structural element of the machine fixed with respect to the transverse movement of the platen and extending upwardly in front of the platen across the printing line adjacent the printing point to hold the paper away from the ribbon and toward the platen.

25. In a front strike typewriting machine, the combination of a transversely movable rotatable cylindrical platen, means segmentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line thereon and adapted at each printing operation to be moved, substantially vertically, upwardly to carry the ribbon across the printing point thereon, a scale carried by the platen frame and cooperating with the platen and located between the vibrator and the surface of the platen, and paper holding means forming a permanent structural element of the machine fixed with respect to the transverse movement of the platen and extending upwardly in front of the platen across the printing line adjacent the printing point to hold the paper away from the ribbon and toward the platen.
26. In a front strike typewriting machine, the combination of a transversely movable rotatable cylindrical platen, means segmentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line thereon and adapted at each printing operation to be moved, substantially vertically, upwardly to carry the ribbon across the printing point thereon, a scale located below the line of print, paper holding means forming a permanent structural element of the machine fixed with respect to the transverse movement of the platen and extending upwardly in front of the platen across the printing line adjacent the printing point to hold the paper away from the ribbon and toward the platen, and a paper holder traveling with the platen, extending forwardly and downwardly at the front of the platen and terminating above the line of print and above said paper holding means.
27. In a front strike typewriting machine, the combination of a transversely movable rotatable cylindrical platen, means segmentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line
- thereon and adapted at each printing operation to be moved, substantially vertically, upwardly to carry the ribbon across the printing point thereon, paper holding means stationary with respect to the transverse movement of the platen, supported below the platen and extending upward across the printing line thereon adjacent the printing point and adapted to be removed from such operative position, and spring detent means for holding said paper holder definitely in position across the printing line.
28. In a front strike typewriting machine, the combination of a transversely movable rotatable cylindrical platen, means segmentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line thereon and adapted at each printing operation to be moved, substantially vertically, upwardly to carry the ribbon across the printing point thereon, and paper holding means forming a permanent structural element of the machine stationary with respect to the transverse movement of the platen and extending upwardly in front of the platen across the printing line adjacent the printing point and terminating a short distance above the upper edge of the vibrator.
29. In a front strike typewriting machine, the combination of a transversely movable rotatable cylindrical platen, means segmentally arranged transversely of the machine below and opposite the printing point on the platen for pivotally supporting type bars that are adapted to lie below the platen and extend toward the front of the machine, a centrally disposed ribbon vibrator adjacent the front face of the platen and also the printing line thereon and adapted at each printing operation to be moved, substantially vertically, upwardly to carry the ribbon across the printing point thereon, and paper holding means provided with a paper deflecting portion and forming a permanent structural element of the machine fixed with respect to the transverse movement of the platen and extending upwardly in front of the platen across the printing line adjacent the printing point to hold the paper away from the ribbon and toward the platen.

In testimony whereof, I have hereunto subscribed my name.
